UNITED STATES PATENT OFFICE.

CHARLES S. BAUM, OF WILLIAMSPORT, PENNSYLVANIA.

GOVERNOR OR CHIN-REST FOR HORSES.

SPECIFICATION forming part of Letters Patent No. 591,726, dated October 12, 1897.

Application filed January 27, 1897. Serial No. 620,915. (No model.)

To all whom it may concern:

Be it known that I, CHARLES S. BAUM, a citizen of the United States, residing at Williamsport, in the county of Lycoming and

5 State of Pennsylvania, have invented certain new and useful Improvements in Governors or Chin-Rests for Horses; and I do hereby declare the following to be a full, clear, and exact description of the invention, such as will 10 enable others skilled in the art to which it appertains to make and use the same.

My invention relates to improvements in devices for governing or controlling a horse while trotting, to give him a chin-rest, to permit 15 a more perfect control over the animal by the driver, to prevent him "breaking" in trotting, and to hold his mouth closed, so that he will be compelled to breathe through his nostrils, and will not permit him to get his 20 tongue over the bit.

With these and other objects in view my invention consists in the construction, arrangement, and combination of parts and in the various details thereof, as will be first 25 fully pointed out in the specification and then claimed.

In the drawings forming a part of this specification and in which like symbols of reference represent corresponding parts in both 30 views, Figure 1 is a perspective view of my improvement applied to a horse; and Fig. 2 is a plan view of the levers and nose-band, partly broken away to show the pivoted connection of the nose-band to the levers and the 35 face-pieces secured to the nose-band.

A represents the levers of my improved device, which in use naturally rest on each side of the face of the horse, B the nose-band, pivoted to the levers by bolts c, and C the over- 40 draw-rings of the levers.

F are the overdraw-straps, which are attached to the overdraw-rings C of the levers, D the chin-strap, and d the chin-strap rings.

E are the usual face-pieces of the bridle, 45 formed from a single strap, passing under the brow-band and buckled to the upper part of the same, preferably to the crown-piece, and, passing down on either side of the face of the horse, are joined to the nose-band. By means 50 of these face-pieces the governor may be adjusted to its proper position on the horse's

nose, the upper portion of the face-pieces, as before mentioned, being buckled to the halter or bridle, so that it may be regulated as desired.

55

To hold the nose-band in its proper shape and also to make its pivoted relation to the levers durable and strong, I place immediately below the leather portion e the metallic band f, which holds the same securely in 60 shape, giving it a spring action, and the rivets or bolts c, passing through the same, permit the levers to oscillate or turn upon the same, the nose-band being held in position by the face-pieces E and the swiveling action being entirely in the levers.

m is a rivet passing through the metallic strip and through the leather e, so as to hold the leather portion of the nose-band in proper relation to the spring f. By this means there 70 is no abrading or rubbing of the horse's nose by the nose-band, a thing so common in devices of this character.

The nose-band is preferably lined with felt and chamois-skin, so as to present a soft surface to the horse's nose.

Just below the rings C is a spreader bar or rod h, joining the two levers and holding them firmly in their proper relation to each other.

Of course it will be understood that my 80 overdraw or checkrein straps F may, after they pass over the head of the horse or through the crown-piece, meet in a common strap, or they may continue double—that is, may be continued as individual straps, in the nature 85 of an ordinary check.

The levers A of my device are substantially L-shaped or angular in form, the upper portion being considerably longer from the pivot c, or about double the length of the lower portion, as will be apparent from the drawings, the said arrangement permitting a better leverage and control of the horse.

I have not described the portions of the bridle in connection with my invention, as I 95 consider the same immaterial, my improvement being applicable to any of the bridles ordinarily used.

It will be apparent that the usual buckles for the overdraw, chin-rest, &c., will be employed for regulating the various parts of my 100 device.

Having now fully described my invention, what I claim as new, and desire to secure by Letters Patent, is—

1. In a governor for horses, the combination with the nose-band thereof having a spring within the same, of angular levers pivotally connected to the nose-band, said connection being at and within the angle of said levers, overdraw-rings on said levers for attachment to the overdraw or check, and chin-strap rings on the levers for attachment of the chin-strap, so that the pressure on the chin-strap and overdraw will be uniform.
2. In a governor for horses, the combination with the angular levers thereof, of a nose-

band pivotally connected to and lying within said levers, the pivotal connection being at the angle of said levers, rings on each of the free ends of the levers for attachment of the overdraw and chin-reststraps, and face-pieces 20 connected with the nose-band, so that the nose-band may be properly adjusted upon the horse.

In testimony whereof I affix my signature in the presence of two witnesses.

CHARLES S. BAUM.
